LIFEBOAT LAUNCHING APPARATUS

John L. Hyland, New York, N. Y.

Application March 12, 1931, Serial No. 522,027

17 Claims. (Cl. 9—22)

This invention relates to an improvement in lifeboat launching apparatus, of the type set forth in my former application Serial No. 478,452, filed August 28, 1930.

5. In the apparatus set forth in the said application, the lifeboat is normally carried over a side of the deck of the boat and is adapted to be turned around through 180° to be disposed off of the side of the deck in position to be lowered.
10. It is the object of this invention to facilitate this turning of the lifeboat and to provide power means therefor, which will not only effectively turn the boat but will also securely hold the boat in either of its extreme positions, and when stored 15 on the deck this holding means effectively ties the boat in place, and also holds the davits in place at all times.

In the accompanying drawing:

- Fig. 1 is a top plan view of the apparatus;
20 Fig. 2 is a detail side elevation of a portion of the lowering mechanism; and

- Fig. 3 is a partial side elevation of the supporting structure and sheaves.

A lifeboat cover is designated generally by the 25 numeral 1 and has the lifeboat supported therebeneath and is carried by a suitable frame 2, which has an angular support 3 fixed thereto and is pivotally supported about the axis of a bolt 4, which bolt extends through one side of an 30 angle-iron supporting truss 5 extending longitudinally of an edge of the deck, and is spaced thereabove a distance sufficient to accommodate the boat and its supporting mechanism. The frame 2 carries guard rails 6 therein, all of which 35 turns upon turning the boat about its pivot 4.

The truss 5 is provided with tie rods 7 on opposite sides of the launching apparatus and has an intermediate tie rod 8, which is connected with the bolt 4. Each of these tie rods has one end 40 fixed to the truss 5 and has its opposite end extending through or fixed to a wall or support 9 extending upwardly from the deck of the boat and which may be one side of a cabin, where located sufficiently close to the edge of the deck.

45. In order to apply power to turn the lifeboat, a central sheave 10 is supported by the truss 5 between the same and the angular support 3 at the axis of the bolt 4, and secondary sheaves 11 are arranged on opposite sides thereof, each 50 of which sheaves 11 is carried by the truss 5.

Sheaves 12 and 13 are fixed to and carried by the angular support 3. A cable 14 extends about the sheaves 10, 11, 12 and 13 and is given a complete turn around the sheave 12 to anchor the 55 same to said sheave.

One end of the cable 14 is coiled about a cone 15 fixed to a shaft 16, which shaft is mounted in brackets 17 carried by the wall 9. The cable 14 has one end fixed to the cone 15. The opposite end of the cable 14 is coiled about a cone 18 arranged at the opposite end of the shaft 16 from the cone 15 and has its end fixed to said cone 18 and is coiled therearound in a direction opposite to the direction of coiling around the cone 15. It will be noted that the cones 15 and 18 are turned with the small ends in opposite directions, so that when the shaft 16 is rotated, the cable is uncoiled from the large end of one cone and is coiled onto the small end of the other, at the starting of the turning movement, but near 15 its completion, this is reversed. This provides a sufficient amount of slack in the cable to maintain the same taut throughout the turning movement.

The shaft 16 has a worm wheel 19 fixed thereto 20 and with which a worm 20, as shown in Fig. 2, meshes to turn the shaft 16. A handle 21 is connected with the worm 20 to turn the same. While the worm and worm wheel are shown as the source of power for turning the lifeboat, yet any 25 other suitable power may be employed as may be found desirable, but the worm serves as a lock to hold the lifeboat in any set position.

The form of lowering mechanism illustrated in my application Serial No. 478,452, filed August 28, 1930, may be employed if desired, and a portion of which is shown at 22, which illustrates the hand-wheel for lowering the cables attached to the lifeboat.

As a means of stopping the turning movement 35 in either direction, a crank rod 23 is interposed between the truss 5 and the deck of the boat and is pivotally mounted in position to be engaged by the frame 2 when turned to an extreme position.

The crank rod 23 may swing to either side of 40 the center of the frame 2 to allow the frame to be disposed in a proper intermediate position and yet to stop the turning movement thereof.

In the operation of the apparatus, the lifeboat is normally disposed in a position over the deck 45 of the boat and behind the axis of the bolt 4 about which it turns. When in the position shown in full lines in Fig. 1, the lifeboat is ready to be lowered and has been turned to a position outside of the deck. This turning movement is 50 accomplished by the cable 14 which is successively unwound and wound onto the cones 18 and 15, upon rotation of the shaft 16 by the worm wheel 19, worm 20 and handle 21. In moving the lifeboat from the full line position of Fig. 1 55

into a stored position, the handle 21 is rotated to cause an unwinding of the cable from the cone 18, and a winding thereof onto the cone 15. As the cable extends about the sheaves 11, 5 13 and 19 and being secured to the sheave 12, it causes a pulling on the latter to turn the same in a general outwardly direction, as shown by the arrow in Fig. 1 tending to move the parts to their dotted line positions in Fig. 1.

10 As the sheave 13 moves around sufficiently far, the cable 14 engages only one of the sheaves 11, and the sheave 13 moves out of contact with the cable until the parts have assumed a position almost the reverse of the full line position in 15 Fig. 1, when the sheave 13 has moved to the position occupied by the sheave 12 in Fig. 1, and the sheave 12 has moved to the position of the sheave 13. The sheaves 11, 12 and 13 over which the cable extends maintain the same taut 20 so as to effectively bind the lifeboat to the deck at all times, and when it has been moved to its stored position, the cable serves to effectively hold the same in position.

Where there is not sufficient room between the 25 edge of the deck and the cabin for the lifeboat to turn, the latter may be placed off-center or with a greater portion of it at one side of its axis to permit of this turning action.

If it should be desired, as in a battleship, the 30 apparatus may be placed in the hull of the ship instead of on the deck, in which event it may be completely loaded before being turned, and the guard rails will protect the passengers during loading.

35 I claim:

1. In lifeboat launching apparatus, the combination of a supporting frame for the lifeboat, a supporting truss, a pivotal support for the frame having a vertical turning axis and connected with 40 the truss to permit turning of the lifeboat relative to the truss, a power cable connected with the frame for causing said turning movement, and guiding sheaves carried by the truss and frame.

45 2. In lifeboat launching apparatus, the combination of a supporting frame for the lifeboat, a supporting truss, a pivotal support for the frame having a vertical turning axis and connected with the truss to permit turning of the lifeboat 50 relative to the truss, a power cable connected with the frame for causing said turning movement, sheaves carried by the truss and frame and about which said cable extends, and power operated means connected with the cable for moving the 55 same about the sheaves.

3. In lifeboat launching apparatus, the combination of a supporting frame for a lifeboat, a pivotal support for said frame, a cable operatively connected with said frame for causing turning 60 movement thereof, and cone-shaped members receiving the opposite ends of said cable, said cable having its opposite ends wound onto the small and large ends respectively of said cone-shaped members.

65 4. In lifeboat launching apparatus, the combination of a supporting frame for a lifeboat, a pivotal support for said frame, a cable operatively connected with said frame for causing turning movement thereof, cone-shaped members receiving 70 the opposite ends of said cable, said cable having its opposite ends wound onto the small and large ends respectively of said cone-shaped members in opposite directions, a shaft for supporting said cone-shaped members, and gearing 75 for rotating said shaft.

5. In lifeboat launching apparatus, the combination of a supporting frame for a lifeboat, means for pivotally supporting said frame for turning movement, and a crank rod mounted for turning movement on its axis and in position to be engaged by the frame during said turning movement to stop the turning movement of the frame in different directions. 5

6. In lifeboat launching apparatus, the combination of a stationary frame, a supporting frame 10 for a lifeboat, pivotal means for said supporting frame for turning movement relative to the stationary frame, and a crank rod having a vertical turning axis carried by the stationary frame to engage the supporting frame and limit the turn- 15 ing movement thereof.

7. In lifeboat launching apparatus, the combination of a supporting frame for a lifeboat, a pivotal support having a vertical turning axis for said frame, a power cable for turning the frame 20 on its pivotal support, and sheaves carried by the frame and constructed and arranged thereon for maintaining the cable taut during said turning movement.

8. In lifeboat launching apparatus, the combination of a supporting frame for a lifeboat, a pivotal support for said frame, a power cable for turning the frame on its pivotal support, and stationary and movable sheaves for engaging the power cable, said sheaves being constructed and 30 arranged for maintaining the cable taut during said turning movement.

9. In lifeboat launching apparatus, the combination of a stationary frame, a supporting frame for a lifeboat, a pivotal support for said supporting frame, a power cable for turning the supporting frame on its pivotal support, and sheaves carried by the stationary and supporting frames and arranged to engage the cable during turning movement to maintain the cable taut. 35 40

10. In lifeboat launching apparatus, the combination of a lifeboat support mounted on the hull of a ship, a pivot for the support having an upright turning axis, sheaves mounted on said support on opposite sides of said pivot, and a cable 45 extending over said sheaves for turning the support on the pivot.

11. In lifeboat launching apparatus, the combination of a lifeboat support mounted on the hull of a ship, a pivot for the support having an upright turning axis, sheaves mounted on said support on opposite sides horizontally of said pivot, a cable extending over said sheaves for turning the support on its pivot, and guide means carried by the support in position to engage the cable intermediate the spaced sheaves during said turning movement to maintain the cable taut. 50 55

12. In lifeboat launching apparatus, the combination of a lifeboat support, means for pivotally supporting said support for turning movement about an upright axis, an upright crank-rod having its opposite end portions journaled for turning movement and having an intermediate crank portion in position to be engaged by the swinging movement of the support to limit said swinging movement. 60 65

13. In lifeboat launching apparatus, the combination of a fixed supporting frame carried by the deck of a ship, a second frame pivotally supported by the fixed frame and having the major portion thereof lying in a vertical plane and supporting a lifeboat for turning movement about a fixed vertical axis located in said vertical plane and at the edge of the deck and at one side of 70 75

the lifeboat intermediate the ends of the lifeboat in stored position.

14. In lifeboat launching apparatus, the combination of a fixed frame having an approximately horizontal truss supported above the deck of a ship, a second frame pivotally supported by the fixed frame and mounted beneath the truss of the frame and pivotally connected thereto for turning movement about a vertical axis fixed relative to the hull of the ship, means connected with the second frame for supporting a lifeboat, and power operated means for causing turning movement of the second frame relative to the fixed frame.

15. In lifeboat launching apparatus, the combination of a frame carried by the hull of a ship for supporting a lifeboat, a vertical pivot for said frame at one side edge of the lifeboat intermediate the ends of the frame with the ends of the frame extending horizontally on opposite sides of said pivot to permit the turning thereof, a cable operatively connected with and for turning the frame about the pivot, and means for applying power to said cable to cause said turning movement.

16. In lifeboat launching apparatus, the combination of a frame carried by the hull of a ship

and extending horizontally in a vertical plane for supporting a lifeboat, a fixed pivotal support for said frame having a vertical turning axis and arranged to swing the lifeboat off of the deck of the ship when the frame is turned about the axis of said pivotal support to one position, a power cable connected with the frame for causing turning movement thereof, sheaves for guiding the power cable, and power operated means connected with the cable for moving the same to turn the lifeboat.

17. In lifeboat launching apparatus, the combination of a stationary frame, a movable frame for supporting a lifeboat, means for pivotally supporting said movable frame for turning movement, and a crank-rod having vertically extending end portions, one of which is connected with the stationary frame, said end portions forming pivotal supports for the crank-rod for swinging movement of said crank-rod in opposite directions about a vertical axis to be engaged by the movable frame on reaching the limits of its turning movement.
